UNITED STATES PATENT OFFICE.

WILBERN S. BEEMAN, OF KANSAS CITY, MISSOURI.

STREET-SWEEPER.

No. 897,705.

Specification of Letters Patent.

Patented Sept. 1, 1908.

Application filed April 12, 1907. Serial No. 367,766.

To all whom it may concern:

Be it known that I, WILBERN S. BEEMAN, a citizen of the United States, and a resident of Kansas City, in the county of Jackson and 5 State of Missouri, have invented a new and Improved Street-Sweeper, of which the following is a full, clear, and exact description.

The invention has in view the production of a street sweeper carried by and forming a 10 part of a motor vehicle, preferably of the automobile type, and in which the sweeping mechanism is driven from the vehicle motor.

In the operation of the sweeper, the sweepings are collected and delivered into the 15 vehicle body, the latter being shiftable on the running gear of the machine to carry it to and from a dumping position. Provision is made for the sprinkling of the street by the sweeper in advance of the brush, whereby the dust is 20 allayed, and for the elevation of the brush and connecting mechanism upon the vehicle body when it is to be thrown out of action.

Reference is to be had to the accompanying drawings forming a part of this specification, 25 in which similar characters of reference indicate corresponding parts in all the figures.

Figure 1 is a plan of the sweeper complete showing the brush and connecting mechanism in operative position; Fig. 2 is a side 30 elevation of the same; Fig. 3 is a central, longitudinal section through the rear portion of the machine; Fig. 4 is a section on the line 4—4 of Fig. 2 looking rearwardly; Fig. 5 is a section on the line 5—5 of Fig. 2, looking in 35 the same direction, and Fig. 6 is an inverted plan of the forward portion of the machine, showing a portion of the mechanism for shifting the body of the sweeper.

The forward portion of the sweeper presents the same appearance and is of the same 40 general construction as the ordinary type of automobile except that the power transmission is slightly modified to meet the special requirements of this type of machine. The 45 rear portion of the sweeper is considerably increased in width and carries a box-body 10 movable on rollers 11, journaled at opposite sides of the frame of the running gear or chassis, three rollers being provided which 50 are respectively positioned at the rear of the driver's seat, at the rear of the machine and in an intermediate position. The running gear also carries a tank 12 which is suspended underneath and extends the full length of the 55 machine. The motor of the machine which is preferably a steam engine, may have the

batter supplied from the tank 12 and the exhaust discharged directly into the tank, which will overcome the disadvantages of exhausting into the air.

As shown in Fig. 6 and in dotted outline in Fig. 1, a countershaft 13 is connected up with the motor in any suitable manner such that it may be controlled from the driver's seat in driving it in either direction or rendering it 60 inactive. Fixed to the shaft 13 is a bevel pinion 14 shown in Fig. 2, which is engaged by a bevel pinion 15 secured to the lower end of an inclined shaft 16. This last-named shaft carries at its opposite and upper end a worm 17 in mesh with a worm-wheel 18 carried by a shaft 19 which is supported in suitable bearings and in turn carries a drum 20. A cable 21 is wound intermediate its length about the drum 20 and has the opposite ends 70 thereof passing over sheaves 22 and 23, respectively arranged and supported at the top and bottom and at the rear of the driver's seat. The end of the cable passing over the sheave 23 passes under the rollers 11 and is 80 connected to the bottom of the body 10 near its inner end. The opposite end of the cable passes directly to and is connected with the inner end of said body.

The driving shaft of the engine, as shown 85 in dotted outline in Fig. 1, is provided with a bevel pinion 24 in mesh with a similar pinion 25 attached to a cross shaft 26, the latter being extended beyond the machine at each side where it is provided with sprocket-wheels 27, one end of this shaft being also provided with a sprocket-wheel 28 arranged at the outside of the adjacent sprocket-wheel 27 and connected with a larger sprocket-wheel 29 by a chain 30 this last-named 95 sprocket-wheel being carried on the rear axle of the sweeper through which the machine is propelled.

The sprocket-wheels 27, by chains 31, are connected with said drive sprocket-wheels 32 100 idly mounted on studs near the rear axle and also in fixed relation each with a gear 33 in mesh with a gear 34, each gear 34 being journaled on a bearing carried by an L-shaped arm 35, said arm being pivoted eccentric to 105 the gear 34 at a point 36. The arms are slideable within keepers 37 carried at the sides of the body 10 and are constructed with horizontally-extended portions 38 at their extremities, as best shown in Fig. 1. Each 110 arm 35 is normally forced in a rearwardly direction by a spring 39 which operates to keep

the gears 33 and 34 in mesh when the sweeping mechanism is in operative position.

Meshing with the gear 34 at each side of the machine, is a gear 40 having a sprocket-wheel 41 in fixed relation therewith, which is connected with a similar sprocket-wheel 42 by a chain 43. The sprocket-wheels 42 are fixed to the opposite reduced ends of a roller 44, which is journaled in bearings carried at the top center of the body 10. A similar roller 45 is slideable in guideways 46 fixed to the rear half of the body 10, the guideways 46 being slightly depressed at their rear ends to retain the roller in operative position when slid thereto.

In mesh with the gears 40 at the opposite sides of the machine, are gears 47 connected with sprocket-wheels 48 on shafts which form the pivotal connection of arms or links 49, said links being in turn pivotally attached to links 50 and adapted to be retained in alignment therewith by loops 51 slideable over the adjacent ends of each pair of links. As shown in Fig. 1, the link 50 at the right of the machine is offset to carry it beyond the hub of the rear wheel at this side of the sweeper, and thus permits a revoluble brush 52 which is journaled between the free ends of the links 50, to pass close to the curb of the street when the sweeper is in action. The axle of the brush 52 is extended beyond the link 50 at the left of the machine and carries a sprocket-wheel 53 which is connected with and driven from the sprocket-wheel 48 by a chain 54. As shown in detail in Fig. 5, the point of pivotal connection between the links 50 and 51 is provided with suitably-supported rollers 55 which overhang and contact with the bottom and top links of the chain 54. Rigidly secured to the links 50 adjacent to the brush 52, is a pan 56 which is provided with wheels 57 designed to travel on the ground and assist in supporting this part of the sweeping mechanism when the machine is in operation. The construction of this pan as best shown in Fig. 3, comprises a flanged outer edge 58 conforming to the brush 52, which prevents the sweepings from wasting out after being collected. A roller 59 is journaled crosswise of the pan adjacent to the flange 58 and receives thereabout an elevator consisting of an apron 60 having buckets 61. This elevator is provided with chains 62 at opposite edges adapted to engage with sprocket-wheels 63 secured to a shaft 64 journaled near the top and at the tail end of the body. The elevator also passes over the rollers 44 and 45, the roller 44 acting to drive the elevator and deliver the sweepings from the brush 52 and pan 56 when these parts are disposed in operative position.

In the sides of the body 10 near the top front end thereof is journaled a cross shaft 65, having drums 66 fixed at opposite ends

at the outside of the body, which are to be operated by cranks 67. A line 68 is wound about each drum 66 and passes over guide rollers 69 carried by the body near the chain 43, the line extending from this point to the adjacent link 50 to which it is connected. By this construction, when the brush and elevator are to be thrown out of action, by sliding back the loops 51 and winding up the line 68 by the operation of the crank 67, the brush, pan and elevator are carried by the cranks to an elevated position over the top of the body 10, the links 49 assuming a vertical position with the links 50 at right angles thereto resting on brackets 70 attached to the body 10, this inoperative position of the brush and connecting parts being shown in dotted outline in Fig. 2 and in full lines in Fig. 3. During the elevation of the brush, the links 49 strike the extended portions 38 of the arms 35 and throw the gears 34 out of mesh with the gears 40 and thereby render the gear 40 and connected gearing inactive when the brush is in inoperative position.

When the sweeper is in operation, a large portion of the sweepings is thrown directly upon the elevator, a part, however, being thrown into the pan 56 and is scooped out by the buckets of the elevator which delivers all of the sweepings into the box body. When it is desired to dump this body, power is applied to the driving mechanism of the drum 20 in a direction to pull on the bottom length of the cable 21. This draws the body to the rear of the machine over the rollers 100 11, causing it to drop to an inclined position, as illustrated in Fig. 3. A tail-gate 71 carried by the body is preferably hinged at the top and secured in any suitable manner at its lower edge. This gate is released when the box body is shifted from the body of the machine and admits of the sweepings sliding out after the sweeper has been dumped. The operator by causing the drum 20 to be driven in the opposite direction again draws the body back upon the bed of the vehicle. A suitable sprinkler 72 is connected with the tank 12 and is controlled from the driver's seat by a lever 73 and operates to spray the water from the tank in advance of the brush and thus allay the dust.

The construction of my improved sweeper as illustrated and as hereinbefore described, is the preferred embodiment of my invention which is susceptible of numerous modifications falling within the scope of the annexed claims.

Having thus described my invention I claim as new and desire to secure by Letters Patent:

1. In a vehicle, a body, a brush, means for delivering the sweepings from the brush into the body, means for swinging the brush over the body, and means for shifting the body from the vehicle to a dumping position.

2. In a street sweeper, a vehicle having outer and inner links pivoted together, said links being swingingly mounted at the opposite sides of the vehicle, a revoluble brush journaled between the outer links, means for driving the brush including a chain drive arranged along the side of one of the outer and inner links, means for swinging the links and brush to an elevated position whereby the outer links assume a position at substantially right angles to the inner links, and means carried at the pivotal connection of the outer and inner links adjacent to said drive automatically operating to hold the chain of said drive in engagement with the driving and driven parts when the links are disposed in said position.
3. In a street sweeper, a motor vehicle, a revoluble brush, means for driving the brush from the motor of said vehicle, means for swinging the brush to an inoperative position above the vehicle, and means automatically operating to throw the brush out of gear with said motor when swung to said position.
4. In a street sweeper, a vehicle, outer and inner links pivotally connected together and swingingly mounted at the opposite sides of the vehicle, a brush journaled between the outer links, means for holding the links in substantial alinement and extended at the rear of the vehicle when the brush is in operative position, and means for elevating the brush over the vehicle with the outer links disposed at substantially right-angles to the inner links.
5. In a street sweeper, a vehicle having a box body, inner and outer links pivotally connected together swingingly mounted at the opposite sides of the box body, a brush journaled between the outer links, brackets attached to the opposite sides of the body, and means for swinging the brush over the body to bring the outer links to rest on said brackets and at substantially right-angles to the inner links.
6. In a street sweeper, a motor vehicle having a box body, a revoluble brush, means for driving the brush from the motor of the vehicle, means for delivering the sweepings from the brush into the body, and means to carry the brush over the body automatically operating to disconnect it from the motor of the vehicle.
7. The combination of a motor vehicle having a box body, a fixed roller and a slideable roller carried by the box body, arms pivotally supported at the opposite sides of the body, a revoluble brush journaled between said arms, a pan secured between the arms adjacent to the brush, a roller journaled in the pan, and an apron passing over all of said rollers.
8. The combination of a motor vehicle having a box body, sweeping means and delivering means carried by the body, gearing journaled on the side of the body for driving said sweeping and delivering means, means for driving said gearing from the motor of the vehicle, and means for moving said body to and from the vehicle for dumping the sweepings, operable to connect and disconnect said gearing with the last mentioned means.

In testimony whereof I have signed my name to this specification in the presence of two subscribing witnesses.

WILBERN S. BEEMAN.
